UNITED STATES PATENT OFFICE.

GEORGE C. RICHARDS, OF BERKELEY, CALIFORNIA.

ROLLER-MILL.

1,264,558.

Specification of Letters Patent. Patented Apr. 30, 1918.

Application filed April 17, 1917. Serial No. 162,742.

To all whom it may concern:

Be it known that I, GEORGE C. RICHARDS, a citizen of the United States, residing at Berkeley, in the county of Alameda and 5 State of California, have invented new and useful Improvements in Roller-Mills, of which the following is a specification.

This invention relates to a grinding mill of the centrifugal roller type.

10 One of the objects of the present invention is to provide a simple, compact grinding mill of the centrifugal roller type, which is particularly adapted for pulverizing and amalgamating gold ores for recrushing the tailings for jigs and reducing the ore for concentration. Another object of the invention is to provide an annular grinding pan employing renewable and bottom dies and a plurality of cone-shaped grinding rollers 15 supported in the pan without journals and having grinding faces formed thereon engageable both with the end and the bottom dies. Another object of the invention is to provide a plurality of propelling arms, one 20 for each roller, and a shoe for each arm engageable with the roller and having three functions: First, each shoe forms a driver for the roller; second, each shoe forms a grinding face between the roller and the 25 shoe; and, third, each shoe forms a grinding face between the shoe and the bottom dies. Another object of the invention is to provide a continuous slanting annular screen 30 discharge of large area and capacity. Further objects will hereinafter appear.

The invention consists of the parts and the construction and combination of parts as hereinafter more fully described and claimed, having reference to the accompanying drawings, in which—

Figure 1 is a central, vertical section through the grinding mill.

Fig. 2 is a plan section on line 2—2 of Fig. 1.

Fig. 3 is a perspective detail view of a grinding unit comprising a roller and a shoe.

Fig. 4 is a vertical, longitudinal section through one of the grinding rollers.

Referring to the drawings in detail, A indicates a circular pan, in the bottom of which is placed a suitable number of removable and renewable die plates 2. Formed around the outer edge of the pan is an annular rim 3, and supported against said rim, interiorly 50 thereof, is a plurality of removable and renewable end dies 4. Extending upwardly

from the annular rim section 3 is a plurality of arms 5, and supported by said arms is an upper housing 6 which supports a cover plate 7.

Formed in the center portion of the pan is a bearing 8, and extending through said bearing and a second bearing formed in the cover plate 7 is a driving shaft 9, to which power may be transmitted in any suitable 60 manner, or, as here shown, by means of a pair of bevel gears 10. Keyed or otherwise secured to the shaft and supported against endwise movement by the upper end of the bearing 8 is a hub member 11, and formed integrally therewith is a plurality of downwardly extending, radially disposed arms 12.

Suitably secured within the housing 6 is a centrally disposed feeding hopper 13, and extending through the cover plate 7 is a 70 feed launder 14 and a water pipe 15, both of which discharge into the hopper 13, which in turn delivers the material to be ground to the central portion of the pan where it is gradually distributed and ground by a plurality of cone-shaped rollers 16. These rollers consist of an inner cast-iron core member 17 and an exterior roller shell 18 which may be made of forged and roller "chrome" steel, or other suitable material, and as thick as desired. The outer end of each shell is tapered, as shown at 19, to engage the end dies in the 75 pan, in this manner forming a grinding face between said dies and the ends of the rollers which has been found highly efficient as 80 it adds considerably to the capacity of the mill.

Pivotaly mounted on the lower end of each arm 12 is a shoe, consisting of a bottom plate 20 and a front plate 21. These plates 95 are preferably formed integral and each is provided with a removable and renewable die plate, such as shown at 22 and 23, respectively. The shoes are mounted behind the rollers and as they are pivotaly mounted 100 in the arms 12, which revolve with the driving shaft, it can readily be seen that they will engage the rear sides of the rollers and push or roll the same around the pan. In other words, each shoe forms a driver for an 105 individual roller and it also forms two more grinding faces, one between the roller and the front die 22 and one between the die 23 and the main bottom dies in the pan. Each grinding unit, consisting of a roller and a 110 shoe, is, therefore, provided with four separate and independent grinding faces. First,

the main outer surface of the roller engages the bottom dies while rolling around the pan; second, the outer beveled end of each roller engages with the annularly arranged end dies 4, thereby forming a second grinding surface; third, the die 22 engages the rear side of the roller, in this manner forming a third grinding face; while engagement of the die 23 with the main bottom dies 5 forms a fourth grinding face. The grinding capacity of the mill is, therefore, enormously increased, when compared with the centrifugal roller mills now employed as three efficient grinding surfaces have been added.

15 The pivotal mounting of each shoe with relation to the driving arm 12 permits the whole weight of the shoe and the dies carried thereby to be exerted upon the dies 23 and the main bottom dies 4. This is of considerable importance as it permits the material treated to be finely ground by the grinding action of the shoe. The pivot pins, by which the shoes are connected to the arms, are preferably passed through slots 24 formed in the lower ends of the arms to permit each shoe to rise and fall, or, in other words, adjust itself to the quantity of material delivered to the pan. The lower edge of the die 22 and the front edge of the die 23 are preferably tapered off, as shown at 25, to permit the admission of material between the grinding faces, and as they are both removable and renewable, it can readily be seen that the life of each shoe is practically unlimited. This is also true as far as the rollers are concerned; that is, a roller shell 18 when worn too thin may easily be renewed by removing it from the core and applying a new shell which is secured by 30 means of wooden or metal bushings, as shown at 26.

In actual operation, it has been found that the outward or centrifugal force exerted when the rollers are traveling at a certain speed enormously increases the grinding capacity between the ends of the rollers and the dies 4. This, together with the several other grinding surfaces provided, insures an unprecedented capacity and as a discharging screen 30, also having a large capacity, extending around the pan is provided, it can be seen that the free discharge of the material ground will always be permitted.

The screen may be made in several sections which are secured in frames supported in channels 31 formed in the arms 5. They can be easily removed, when desired, and a fine meshed screen can at the same time be provided as each screen section or frame is comparatively small.

A mill constructed as here shown is simple in construction and is exceedingly compact in size for the quantity of material handled. The life of the mill is further

65 more practically unlimited as all wearing

parts, such as rollers and dies, may be renewed, when desired, and as no journals and lubrication are required, as far as the rollers are concerned, it can readily be seen that the cost of manufacture is furthermore 70 materially reduced. The screen discharge is all around the mill housing instead of in one-half, as is ordinarily the case, and as the feed hopper is centrally disposed an equal distribution and discharge of the ore 75 in front of each roller is permitted, consequently causing an even wear of the rollers and dies.

The materials and finish of the several parts of the device are such as the experience and judgment of the manufacturer may dictate.

I wish it understood that various changes in form, proportions and minor details of construction may be resorted to within the 85 scope of the appended claims and that I do not wish to limit myself to the specific design and construction here shown.

Having thus described my invention, what I claim and desire to secure by Letters Patent is—

1. In a grinding mill, a circular grinding pan, a driving shaft, a plurality of propelling arms secured on the shaft, said arms being slotted at their outer ends, a drag-shoe for each arm engageable with the pan, and a pin on each shoe passing through the slot in each arm to permit a vertical and pivotal movement of each shoe with relation to its propelling arm.

2. In a grinding mill, a circular grinding pan, a driving shaft, a plurality of propelling arms secured on the shaft, a drag-shoe pivotally connected to each arm and engageable with the pan, and a grinding roller 105 adapted to be propelled by each shoe.

3. In a grinding mill, a circular grinding pan, a driving shaft, a plurality of propelling arms secured on the shaft, a drag-shoe pivotally connected to each arm and engageable with the pan, and a freely mounted grinding roller positioned forward of each shoe adapted to be propelled by each shoe.

4. In a grinding mill, a circular grinding pan, a driving shaft, a plurality of propelling arms secured on the shaft, said arms being slotted at their outer ends, a drag-shoe for each arm engageable with the pan, a pin on each shoe passing through the slot in each arm to permit a vertical and pivotal movement of each shoe with relation to its propelling arm, a freely running roller forward of each shoe and an upright section on the front end of each shoe engageable with a roller first to form a grinding surface between each upright section and each roller and secondly to push each roller around the pan ahead of the shoes.

5. In a centrifugal roller mill, a circular 130

grinding pan, bottom dies secured in the pan, an annular row of end dies secured in the pan, a plurality of rollers adapted to travel in a circular path within the pan having end and surface grinding faces formed thereon engageable with the end and bottom dies, a driving shaft, a plurality of propelling arms secured on the shaft, one for each roller, a shoe pivotally mounted on each arm, consisting of a horizontal section and an upright section provided with a co-operating grinding surface, a die plate se-

cured to the forward face of the upright section engageable with a roller, and a die plate secured to the lower face of the horizontal section engageable with the bottom dies. 15

In testimony whereof I have hereunto set my hand in the presence of two subscribing witnesses.

GEORGE C. RICHARDS.
